UNITED STATES PATENT OFFICE

145,700

DESIGN FOR A FLUORESCENT LIGHTING FIXTURE

Nathan M. Robboy, Cleveland Heights, Ohio

Application November 20, 1945, Serial No. 123,925

Term of patent 14 years

(Cl. D48—23)

To all whom it may concern:

Be it known that I, Nathan M. Robboy, a citizen of the United States and a resident of the city of Cleveland Heights, county of Cuyahoga, and State of Ohio, have invented a new, original, and ornamental Design for a Fluorescent Lighting Fixture, of which the following is a specification, reference being had to the accompanying drawing, forming a part thereof.

Figure 1 is a top plan view of the fluorescent lighting fixture, showing my new design;

Figure 2 is a side elevation thereof; and

Figure 3 is an end view thereof.

I claim:

The ornamental design for a fluorescent lighting fixture, substantially as shown.

NATHAN M. ROBBOY.
